UNITED STATES PATENT OFFICE.

VINTON E. SISSON, OF CHICAGO, ILLINOIS, ASSIGNOR TO WALTER P. MURPHY, OF NEW YORK, N. Y.

RAILWAY-CAR.

1,347,878.

Specification of Letters Patent. Patented July 27, 1920.

Application filed April 24, 1919. Serial No. 292,322.

To all whom it may concern:

Be it known that I, VINTON E. SISSON, a citizen of the United States, residing at Chicago, in the county of Cook and State of Illinois, have invented certain new and useful Improvements in Railway-Cars, of which the following is a specification.

My invention relates to the construction of railway cars, and more particularly to the trucks or running gear of the car, and the means for supporting the car body on said trucks or running gear.

According to standard practice the body of a railway car is provided with transverse body bolsters, one for each of the trucks, and the bolster is pivoted, in each case, usually by a center plate and king pin arrangement, to the bolster of the truck which distributes the load to the journal boxes and axles. This method of construction involves the use of two bolsters for each truck, both of which must be very heavy at the center since the entire load on the truck is carried by the portions of the body and truck bolsters which bear one upon the other. As a result the entire construction of the running gear must be relatively heavy.

My invention provides a railway car truck which is constructed upon an entirely different principle. The car body is supported at each side directly upon the journal boxes of the axle so that there is no concentration of the weight of the car on any one point on the body bolster. Moreover, it is possible to do away entirely with the usual truck bolster. The supporting devices at each side of the car consist of coengaging members associated with the journal box and with the end of the body bolster so articulated that relative angular movements are possible between the axle and the car body to give the running gear sufficient flexibility for rounding curves.

By reducing the weight of the body bolster and of the running gear it is possible for a freight car of ordinary size to employ two-wheel trucks instead of the usual four-wheel trucks, thus economizing in material and further reducing the weight of the car.

The principal object of the invention is to provide a railway car truck of this character and more particularly to provide a two-

wheel truck, although the invention might readily be adapted to four or six wheel trucks.

The invention consists in the novel improvements, constructions, arrangements and devices to be hereinafter described and claimed for carrying out the above stated object and such other incidental objects as will appear from the following description of certain preferred embodiments of the invention.

In the drawings,

Figure 1 is a side elevation of a two-wheel truck constructed in accordance with my invention.

Fig. 2 is a fragmentary plan view of one end of the truck.

Fig. 3 is a sectional view on line 3—3 of Fig. 1.

Fig. 4 is a sectional plan on line 4—4 of Fig. 1.

Fig. 5 is a vertical sectional view on line 5—5 of Fig. 2.

Fig. 6 is a sectional view corresponding to Fig. 5 but illustrating a development or modification of the construction shown in the first five figures, and

Fig. 7 is a fragmentary sectional view illustrating another modification.

Like characters of reference designate like parts in the several figures of the drawings.

Referring first to Figs. 1 to 5 inclusive, 10 designates one of the wheels of the car, 11 the axle, 12 the axle journal and 13 one of the journal boxes. In the drawings one end only of the truck is shown. It will be understood that the constructions at the other side of the car will be the same. 14 represents the flooring of the car, 15 the longitudinal sills and 16 a body bolster which extends across the car from side to side.

The journal box 13 is provided preferably on opposite sides with spring supports 17 which are shown as cast integrally with the journal box, although this is not essential. On the spring supports are arranged coiled springs 18, 19 on which is sustained a sliding member 20 having depending channel-shaped webs 21 which lie in vertical recesses 22 formed in the sides of the journal box. The sliding member 20 is provided with a pair of spaced, upstanding webs 23 formed

at the top with bearings 24 for the out-turned gudgeons 25 of a U-shaped hanger 26. The hanger swings on an axis transverse with respect to the car. Connected to 5 and depending from the body bolster 16 is a hanger bracket 27 having webs 28 at right angles to the webs 23 on the sliding member 20, the webs 28 being formed with bearing recesses 29 adapted to receive the ends 10 of a hanger 30, the middle portion of which is formed with an upward bend to provide a seat for engagement with hanger 26. The lower ends of webs 28 stand close to webs 31 forming part of the vertically sliding member 20, the webs 31 being curved so that, as 15 the hanger 26 swings forwardly or backwardly, a uniform distance will be maintained between the lower ends of webs 28 and webs 31, or, if one pair of webs 28, 31 are in contact the hanger 26 may swing 20 without increasing the pressure between the hanger bracket on the car body and the vertically slidable member 20. Preferably the truck structure at one side of the car is connected with the corresponding structure at 25 the other side of the car. In the construction shown in the drawings a pair of angle bars 32 are secured to the lateral projections 33 on the sliding member 20. These angle bars are connected similarly to the sliding member associated with the journal box on 30 the other side of the car.

In Fig. 6 I have shown a development of or improvement upon the truck illustrated 35 in Figs. 1 to 5 inclusive. In the construction shown in Figs. 1 to 5, the hanger bracket on the car body will be likely, in operation, to bear on one side or the other upon one of the webs 31 of the sliding member 20, that is, the sliding member and its journal box will naturally tilt on the journal of the axle one way or the other in accordance with the draft on the car, and this will produce a certain amount of friction 40 tending to hamper the freedom of movement of the hangers. To overcome this I provide, as shown in Fig. 6, a pair of balancing springs which are interposed between the sliding member 20 and the body of the car. 45 These springs are designated 34 in Fig. 6 and are preferably tension and compression springs. One end of the spring, in each case, is secured to a disk 35 having a centering stud 36, the disk being pivoted to a bracket 37 secured to the side of the body bolster 16. The other end of spring 34 is secured within a housing 38 which is pivoted to a bracket 39 secured to one of the lateral projections 33 on the sliding member 20, the transverse angle bar designated 50 32^a in this figure being inverted for convenience in attaching bracket 39.

A somewhat different arrangement is shown in Fig. 7. The hanger bracket associated with the car body, here designated

27^b, is provided with a pair of antifriction rollers 40 adapted to bear upon the webs 31 of the sliding member 20.

In Figs. 6 and 7 the parts not specifically mentioned are the same as corresponding 70 parts in Figs. 1 to 5 and are given the same reference numerals.

Operation: The car body has a floating relation with the running gear giving the body of the car capacity for movement with 75 respect to the running gear both in the direction of the length of the car and also laterally. Within certain narrow limits this relative movement between the body and the running gear of the car is universal with 80 respect to directions in a horizontal plane. As a result the axle may assume an angular position with respect to the car body when the train rounds a curve. The movements of the car body with respect to the wheels 85 are not, however, strictly in a horizontal plane. As any forward or lateral movement of the car body takes place through the pivotal movements of the hangers such longitudinal or lateral movements of the car 90 body involve a lifting of the body from the running gear which is resisted by the weight of the car and these movements are therefore self checking. Any sudden pull on the draft gear of the car, which it will be understood is connected with the body, will result in a slight forward movement of the body with respect to the running gear, and a raising of the car body due to the pivotal suspension thereof. This action helps to relieve the draft gear springs of abnormal 95 stresses in pulling and also in buffing.

I claim:

1. In combination with the body, wheels, axle and journal box of a railway car, of a 105 structure for supporting the car body on the journal box comprising a supporting member and a sliding member associated with the box, cushioning means interposed between said members, and means connecting 110 said sliding member to the car body which has capacity for longitudinal and lateral movements.

2. In combination with the body, wheels, axle and journal box of a railway car, of a 115 structure for supporting the car body on the journal box comprising a supporting member and a sliding member associated with the journal box, means connecting said sliding member to the car body which has capacity for longitudinal and lateral movements, and a cushioning spring interposed 120 between said members which is stressed by said movements.

3. In combination with the body, wheels, 125 axle and journal box of a railway car, of a structure for supporting the car body on the journal box comprising a supporting member and a sliding member associated with the journal box, cushioning means inter- 130

posed between said members, and a pair of pivoted hangers connecting said sliding member to the car body, the pivotal axes of which are at right angles to each other which permit longitudinal and lateral movements of the car body.

4. In combination with the body, wheels, axle and journal box of a railway car, of a structure for supporting the car body on the

10 journal box comprising a supporting member and a sliding member associated with the box, pivoted hangers connecting said sliding member to the car body, the pivotal axes of which are at right angles to each other

15 which permits longitudinal and lateral movements of the car body, and a cushioning spring interposed between said members which is stressed by the oscillation of said hangers.

20 5. In combination with the body, wheels, axle and journal box of a railway car, of a structure for supporting the car body on the journal box comprising a supporting member and a sliding member associated with

25 the box, a spring interposed between said members, and a pair of pivoted hangers connecting said sliding member to the car body, one hanger oscillating on an axis longitudinally of the car and the other oscillating on

30 a transverse axis.

6. In combination with the body, wheels, axle and journal box of a railway car, of a structure for supporting the car body on the journal box comprising a supporting mem-

35 ber and a sliding member associated with the box, a spring interposed between said members, and a pair of pivoted hangers connecting said sliding member to the car body, one oscillating on an axis longitudinally of

40 the car and the other supported by the first-named hanger to oscillate on a transverse axis.

7. In combination with the body, wheels, axle and journal box of a railway car, of a

45 structure for supporting the car body on the journal box comprising a spring support on each side of the box, springs on said supports, a sliding member associated with the box and resting on said springs, and means

50 connecting said sliding member to the car body which has capacity for longitudinal and lateral movements.

8. In combination with the body, wheels, axle and journal boxes of a railway car, of

55 a structure associated with each journal box for supporting the car body thereon comprising a supporting member and a sliding member associated with the box, cushioning means interposed between said members, and

60 means connecting said sliding member to the car body which has capacity for longitudinal and lateral movements.

9. In combination with the body, wheels, axle and journal boxes of a railway car, of a

65 structure associated with each journal box

for supporting the car body thereon comprising a spring support on each side of the box, springs on said supports, a sliding member associated with the box and resting on the springs, and a pair of pivoted hangers connecting said sliding member to the car body, the pivotal axes of which are at right angles to each other which permit longitudinal and lateral movements of the car body.

10. In combination with the body, wheels, axle and journal boxes of a railway car, of a structure associated with each journal box for supporting the car body thereon comprising a spring support on each side of the box, springs on said supports, a sliding member associated with the box and resting on the springs, and a pair of pivoted hangers connecting said sliding member to the car body, one hanger pivoted on an axis longi-

80 tudinal of the car and the other having an oscillating movement on the first-named hanger on a transverse axis.

11. In combination with the body, wheels, axle and journal boxes of a railway car, of a transverse bolster rigid with the body of the car and means for supporting opposite ends of said bolster on the journal boxes respectively, which permits longitudinal and transverse movement of the body of the car.

12. In combination with the body, wheels, axle and journal boxes of a railway car, of a transverse bolster rigid with the body of the car and means for supporting opposite ends of said bolster on the journal boxes, respectively, comprising pairs of pivoted elements having their pivotal axes at right angles with respect to each other whereby the body of the car has a capacity for movement longitudinally and laterally.

13. In combination with the body, wheels, axle and journal boxes of a railway car, of a transverse bolster rigid with the body of the car and means for supporting opposite ends of said bolster on the journal boxes, respectively, comprising cushioning springs and pairs of pivoted elements having their pivotal axes at right angles to each other, whereby the car body has capacity for longitudinal and lateral movement.

14. In a railway car, the combination with the body of the car, a wheel having an axle and a journal box for the axle; of means for supporting the body on the wheel comprising a spring support associated with said box, a spring thereon, a member supported on the spring with capacity for up-and-down sliding movement on the box, and means whereby the body of the car is sustained on said sliding member with capacity for longitudinal and lateral movement.

15. In a railway car, the combination with the body of the car, a wheel having an axle and a journal box for the axle; of means for supporting the body on the wheel

- comprising a spring support associated with said box, a spring thereon, a member supported on the spring with capacity for up-and-down sliding movement on the box, a hanger adapted to oscillate forwardly and backwardly and also laterally with respect to the car for supporting the car body on said sliding member.
16. In a railway car, the combination with the body of the car, a wheel having an axle and a journal box for the axle; of means for supporting the body on the wheel comprising a spring support associated with said box, a spring thereon, a member supported on the spring with capacity for up-and-down sliding movement on the box, and a pair of pivoted hangers oscillating on longitudinal and transverse axes, respectively, for supporting the car body on said sliding member.
17. In a railway car, the combination with the body of the car, a wheel having an axle and a journal box for the axle; of a spring support on each side of the journal box, springs on said supports, a sliding member extending over and around the box and resting on said springs, and means for sustaining the car body on the sliding member with capacity for longitudinal and lateral movement.
18. In a railway car, the combination with the car body, of a pair of wheels at each end of the car body, axles connecting the same, and a structure associated with the end of each axle for supporting the car body thereon comprising a bearing element, a sliding element, cushioning means interposed between said elements, and means connecting the sliding element to the car body with capacity for movement longitudinally and transversely.
19. In a railway car, the combination with the car body, of a pair of wheels at each end of the car body, axles connecting the same, and a structure associated with the end of each axle for supporting the car body thereon comprising a bearing element, a sliding element, cushioning means interposed between said elements, and a pair of pivoted hangers connecting said sliding element to the car body, the pivotal axes of which are at right angles to each other which permits longitudinal and lateral movement of the car body.
20. The combination with the body of a railway car and an axle with its wheels and journal boxes; of means for elastically supporting one side of the car body on each of said journal boxes comprising a member 60 slidable with respect to the journal box, and a pair of hangers arranged above the journal box having rocking movements on each other, and pivoted, with axes at right angles to each other, one to the car body and the other to said sliding member.
21. The combination with the body of a railway car and an axle with its wheels and journal boxes; of means for elastically supporting one side of the car body on each of said journal boxes comprising a member 70 slidable with respect to the journal box formed with a pair of upstanding webs above the journal box, a hanger pivoted to the webs transversely of the car, and means for suspending the car body on said hanger. 75
22. The combination with the body of a railway car and an axle with its wheels and journal boxes; of means for elastically supporting one side of the car body on each of said journal boxes comprising a member 80 slidable with respect to the journal box formed with a pair of upstanding webs above the journal box, a hanger pivoted to the webs transversely of the car, a pair of webs downwardly projecting from the car 85 body, and a hanger engaged by the first named hanger which is pivoted to said last named webs on an axis which is longitudinal of the car.
23. The combination with the body of a 90 railway car and an axle with its wheels and journal boxes; of a member resiliently sustained on the journal box, and flexible suspension devices arranged above the journal box which support the car body on said 95 resiliently sustained member so as to permit movements of the car body with respect to the axle and wheels both in the direction of the length of the car and laterally.
24. The combination with the body of a 100 railway car and an axle with its wheels and journal boxes; of means for elastically supporting one side of the car body on each of said journal boxes comprising a member 105 slidable with respect to the journal box, a pair of hangers arranged above the journal box having rocking movements on each other and pivoted, with axes at right angles to each other, one to the car body and the other to said sliding member, and balancing 110 springs interposed between said sliding member and the body of the car.
25. The combination with the body of a 115 railway car and an axle with its wheels and journal boxes; of means for elastically supporting one side of the car body on each of said journal boxes comprising a member 120 slidable with respect to the journal box formed with a pair of upstanding webs above the journal box, a hanger pivoted to the webs transversely of the car, and balancing 125 springs interposed between said sliding member and the body of the car.
26. The combination with the body of a 130 railway car and an axle with its wheels and journal boxes; of means for elastically supporting one side of the car body on each of said journal boxes comprising a member slidable with respect to the journal box formed with a pair of upstanding webs 130

- above the journal box, a hanger pivoted to the webs transversely of the car, a pair of webs downwardly projecting from the car body, a hanger engaged by the first named 5 hanger which is pivoted to said last named webs on an axis which is longitudinal of the car, and balancing springs interposed between said sliding member and the body of the car.
- 10 27. The combination with the body of a railway car and an axle with its wheels and journal boxes; of a member resiliently sustained on the journal box, flexible suspension devices arranged above the journal box 15 which support the car body on said resiliently sustained member so as to permit movements of the car body with respect to the axle and wheels both in the direction of the length of the car and laterally, and 20 springs interposed between said resiliently sustained member and the car body.
- 25 28. The combination with the body of a railway car and an axle with its wheels and journal boxes; of a bolster on the under side 30 of the car, a hanger bracket secured to the bolster having downwardly projecting webs formed with bearings, a hanger adapted to engage said bearings, the center portion of which is curved, means providing spring supports on opposite sides of said journal box, a sliding member on the journal box, springs interposed between the same and said spring supports, upwardly projecting webs on the sliding member, the upper ends 35 of which are formed with bearings, and a U-shaped hanger having gudgeons engaging said bearings, said hanger adapted to support the first named hanger.
- 40 29. The combination with the body of a railway car and an axle with its wheels and journal boxes; of a bolster on the under side of the car, a hanger bracket secured to the bolster having downwardly projecting webs formed with bearings, a hanger adapted to 45 engage said bearings, the center portion of which is curved, means providing spring supports on opposite sides of said journal box, a sliding member on the journal box, springs interposed between the same and 50 said spring supports, upwardly projecting webs on the sliding member, the upper ends of which are formed with bearings, a U-shaped hanger having gudgeons engaging said bearings, said hanger adapted to support the first named hanger, and a pair of 55 tension and compression springs interposed between the sliding member and the car body.
- 60 30. The combination with the body of a railway car and an axle with its wheels and journal boxes; of a bolster on the under side of the car, a hanger bracket secured to the bolster having downwardly projecting webs formed with bearings, a hanger adapted to 65 engage said bearings, the center portion of which is curved, means providing spring supports on opposite sides of said journal box, a sliding member on the journal box, springs interposed between the same and said spring supports, upwardly projecting webs on the sliding member, the upper ends of which are formed with bearings, a U-shaped hanger having gudgeons engaging said bearings, said hanger adapted to support the first named hanger, and a pair of 70 anti-friction rollers interposed between the hanger bracket on the car body and said sliding member.
- 75 31. The combination with the body of a railway car and an axle with its wheels and journal boxes; of a hanger bracket secured to the car body having downwardly projecting webs formed with bearings, a hanger adapted to engage said bearings, the center portion of which is curved, means providing spring supports on opposite sides of said journal box, a sliding member on the journal box, springs interposed between the same and said spring supports, upwardly projecting webs on the sliding member, the upper ends of which are formed with bearings, a U-shaped hanger having gudgeons engaging said bearings, said hanger adapted to support the first named hanger, and a pair of 80 anti-friction rollers interposed between the hanger bracket on the car body and said sliding member.
- 85 32. In a railway car, the combination with the body of the car, a wheel having an axle and a journal box for the axle; of means for supporting the body on the wheel comprising a supporting member and a sliding member associated with the box, cushioning means interposed between said members, a bracket secured to the car body, 90 means connecting said sliding member to said bracket with capacity for longitudinal and lateral movement, and a pair of anti-friction rollers interposed between the bracket on the car body and said sliding member.
- 95 33. In a railway car, the combination with the body of the car, a pair of wheels, an axle therefor and journal boxes for the axle; of means for supporting opposite sides 100 of the car body on said journal boxes, respectively, comprising in each case a supporting member and a sliding member associated with the journal box, cushioning means interposed between said members, 105 means for sustaining the car body on the sliding member with capacity for movement longitudinally and laterally, and a transverse member connecting said supporting member on one side of the car with that on 110 the other.
- 115 34. In a railway car, the combination with the body of the car, a pair of wheels, 120

- an axle therefor and journal boxes for the axle; of means for supporting opposite sides of the car body on said journal boxes, respectively, comprising in each case a spring supporting member associated with the journal box, a spring on said member, a sliding member having up and down movement with respect to the box and resting on said spring, means connecting the sliding member to the car body with capacity for longitudinal and lateral movement, and a transverse member connecting the spring support on one side of the car with that on the other.
35. In a railway car, the combination with the body of the car, a pair of wheels, an axle therefor and journal boxes for the axle; of means for supporting opposite sides of the car body on said journal boxes, respectively, comprising in each case spring supports associated with the journal box, springs on the supports, a sliding member having up and down movement with respect to the box and resting on said springs, a pair of brackets projecting downwardly from the car body at opposite sides of the box, means for sustaining the brackets on the sliding member with capacity for movement longitudinally and laterally with respect to the running gear of the car, and transverse members connecting the spring supports on one side of the car with those on the other.
36. In combination with the body, wheels, axle and journal box of a railway car, of a structure for supporting the car body on the journal box comprising a supporting member and a sliding member associated with the box, cushioning means interposed between said members, means connecting said sliding member to the car body which has capacity for longitudinal and lateral movement, and balancing springs interposed between said sliding member and the body of the car.
37. In combination with the body, wheels, axle and journal box of a railway car, of a structure for supporting the car body on the journal box comprising a supporting member and a sliding member associated with the journal box, cushioning means interposed between said members, a pair of pivoted hangers connecting the sliding member to the car body, the pivotal axes of which are at right angles to each other which permit longitudinal and lateral movements of the car body, and balancing springs interposed between said sliding member and the body of the car.

VINTON E. SISSON.
